UNITED STATES PATENT OFFICE

FRANCIS J. PLYM, OF NILES, MICHIGAN, ASSIGNOR TO THE KAWNEER COMPANY, OF NILES, MICHIGAN, A CORPORATION OF MICHIGAN

WINDOW CONSTRUCTION

Application filed June 21, 1923. Serial No. 646,761.

My present invention relates to metallic window constructions and more particularly to those in which the sashes are slideable vertically with respect to the frames and among 5 the objects of my invention are to produce a complete building construction unit in the form of a combined window casing and sash; to produce a combined window frame and non-removable or permanently assembled sash; 10 to produce a metallic window casing having a metallic sash permanently mounted therein; to improve upon the mounting of the weight pulleys of a window; to improve upon the construction of window casings; to provide an 15 improved window sash and frame having a weather seal integral therewith; to provide an improved weather seal between relatively slideable window sashes; to produce an improved sash lock; to produce an improved 20 glass securing means; to produce an improved structure of the character stated so that it will not be necessary to remove a portion of the pulley stile to gain access to the sash weights; to construct a metallic window frame or casing 25 so that a portion or portions thereof may be easily removed for access to the sash weights and pulleys; and such further objects, advantages, and capabilities as will later more fully appear and are inherently 30 possessed by the invention.

My invention further resides in the combination, construction and arrangement of parts illustrated in the accompanying drawings and, while I have shown therein a preferred embodiment of my invention, I desire 35 the same to be understood as illustrative only and not as limiting this invention.

In the drawings annexed hereto and forming a part hereof Fig. 1 is a broken elevation 40 of a window embodying my present improvements; Fig. 2 is a broken horizontal section substantially along the plane indicated by the line 2—2 Fig. 1; Fig. 3 is a transverse section showing the relationship of parts before the 45 window glasses are inserted into place; Fig. 4

is a broken vertical section substantially along the plane indicated by the line 4—4 Fig. 1; Fig. 5 is a fragmentary vertical section showing the manner in which the pulley casing is attached to the pulley stile; and Fig. 6 is a 50 broken transverse section showing the relationship of the pulley and its casing to the pulley stile.

Referring more in detail to the annexed drawings, numeral 1 denotes in general the window casing or frame and numerals 2 and 3 the lower and upper sashes, respectively. The frame comprises a pair of side members 4, a head member 5 and a sill 6, the side members having as a part thereof the pulley stiles 55 7 and the head member 5 having the head jamb 8. The side members 4 are made up of a plurality of members, as shown more clearly in Fig. 2, where the pulley stile 7 is shown as being folded over to interfit closely and 60 cooperate with another member, as shown at 9, to form a tight connection and weather seal. An edge 10 is bent outwardly to provide a projection under which a flange 11 of a removable plate 12 may be inserted. The opposite edge of this plate 12 is folded over so 65 that it may be inserted in a groove formed by similarly folding an edge of the pulley stile 7. This forms a tight connection at this point but still leaves it possible to separate the cap 70 plate 12 by the removal of screws 14 which may be of any desired number, two being shown in the drawing. Upon removal of the plate 12 it will be possible to have access to the weights 15 so that they may be easily 75 removed or put in place when desired. A plate 16 is hinged to one interior wall of side member 4 and may be held in proper position by means of springs or otherwise, as desired. After the plate 12 has been removed and the 80 first weight 15 taken out of the opening in the casing, it will be possible to swing the plate 16 out of the way so that the other weight 15 may be brought out through the opening made by the removal of plate 12. It will be 85 90

understood that the weights 15 may be cylindrical, as shown, or rectangular in cross section or may have other desired shapes. Whatever shape is selected, the hinged plate 16 5 serves as a separator to keep the weights from interfering by striking each other.

Near their upper portions, the pulley stiles 7 have portions punched out as indicated at 17 to form the hooks 18 by means of which the pulley casings 19 are held in place. Pulleys 20 are carried by shafts 21 within these casings and over the pulleys pass sash cords 22 which are attached at one end to the sashes and at the opposite end to sash weights 15. 15 In applying the pulley casings 19 to the frame, the hooks 18 are punched out at right angles to the pulley stiles 7 and then passed through openings 23 in flanges of the casings 19. After the casings are in place the hooks 20 18 are bent up and down, respectively, to hold the casings in place, as will be evident from Fig. 5.

As shown in Fig. 2, the pulley stiles 7 are folded during the forming process to form 25 two pairs of grooves as indicated at 24. In this figure the numeral 25 denotes (by dotted lines) the positions of the pulleys 20 and their casings 19. It will thus be seen that each of 30 these casings fits in between a pair of grooves 24 and that the cords 22 coming down from the pulleys 20 will be in position to be attached to the sashes. In the case of the lower sash, any suitable means 26 is used to fasten the rope 22 to the top of the sash, while, in the 35 case of the upper sash, the rope passes through an opening in the top edge thereof and down to a suitable securing means, such as a pin 27 which should be far enough below the level of the axle 21 not to interfere with the pulley 40 when the sash is raised to its uppermost limit. It will be understood from this that there should be an opening in the upper corner of the sash of sufficient size to pass the pulley as the sash is raised.

If desired, the parts may be welded together at 45 or reliance may be placed entirely upon a close fit to prevent moisture and wind from passing through this joint. It is preferable, however, that side members 4, head 50 member 5 and sill 6 should be welded into a unitary whole. Similarly, the side, top, and bottom members of the sashes are welded at the corners to form a unitary construction. The head jamb 8 is provided with a pair of 55 grooves 28 for the reception of the doubled edges 29 of the head rail 30 of the upper sash. In this connection it will be noted that the head rail or top rail 30 of the upper sash, the lower rail 31 of the lower sash and both 60 side rails of both sashes are entirely open along the edge directed away from the glass. It will thus be seen that the construction of all the outer rails of the sashes is the same. While the meeting rails 32 and 33 are not 65 absolutely identical, as shown, they are sub-

stantially so and could, if desired, be made identical. Each of the rails is provided with an abutment 34 formed by appropriate bending of the sheet metal from which the rails are made. Each rail is formed with a groove or pocket 35, formed by bending the metal appropriately, for the reception of one edge 36 of the glass stop 37, a part 38 of which rests against the glass to hold it tightly in place. It will be seen by reference to Fig. 4 that parts 36 and 38 are offset slightly relatively to each other, the purpose of this being pointed out later. Referring more particularly to the lower part of Fig. 1, it will be seen that there is a lower glass stop 39, two lateral 75 stops 40 and an upper stop 41. Assuming that the building has been erected and, during the process of erection, the frame and sashes have been put in position, it will be seen that the sashes are ready to receive the 80 glass 42. After this has been put in position the lower stop 39 is inserted into position by having its portion 36 inserted in the groove 35. Side stops 40 are then put in place in the same manner, thereby locking stop 39 85 in place. Stop 41 has its portion 38 so cut that it will fit in between the stops 40 and it can, therefore, be shoved upwardly into place, portion 36 going into the groove 35. The part 36 of the upper stop 41 as well as the meeting 90 rail 33, is provided with holes for the reception of screws 43 whereby stop 41 is held in place. Since the parts 36 and 38 are not in the same plane, it is possible for part 36 of 95 stop 41 to rest on part 38 of stops 40 while being put into place, but this would be very troublesome if the two parts were not offset laterally from each other. The construction 100 of the upper sash is similar to that of the lower sash.

It will be understood that the glass in both 105 of these sashes may be unitary as well as made in a plurality of pieces, as shown in the drawings. When a plurality of lights of glass is used, muntins or mullions 44 are used to 110 cover the junction between the glasses, as shown in Fig. 2. These mullions comprise outer and inner plates which are secured together by means of a plurality of bolts 45, provided with suitable nuts, as shown in Fig. 2. 115 In setting the glass, use is made of a suitable sealing material 46, for example, putty. This prevents wind and water from passing in 120 between the glass and its mounting, as well as aiding in preventing rattling of the glass.

The sill 6 is provided with a ridge 47 in the plane of the lower sash, as shown in Fig. 4, so that the two sides of the lower rail 31 may come down and engage tightly on opposite sides of this ridge to form a tight 125 joint therewith. The lower rail is provided with one or more handles 48 secured thereto in any desired manner. By means of these the sash can be raised and lowered quite 130 readily.

The meeting sash rails 32 and 33 are provided with a locking device comprising a member 49 suitably secured in the extension 50 of rail 32 and extending upwardly through 5 an aperture 50^a provided in the upper wall of this extension. The protruding portion of the member 49 is of such a length as to extend through an aperture 51^a provided in the extension 51 of the rail 33 and to extend 10 above the latter, the part thus so extending being provided with an aperture or slot 49^a. On the rail 33 is secured a plate 52 by means of screws or bolts 52^a and 52^b. This plate carries a pivot 53 to which is pivoted a latch or hook member 54 having 15 a locking tongue 54^a adapted to be swung into a slot or aperture 49^a and a finger piece 54^b. The member 54 may be swung to one side to relieve the tongue 54^a from the slot 20 49^a in member 49 for unlocking, and to the position shown in Fig. 2 for locking when the tongue 54^a extends through the slot 49^a.

While I have shown and described what is now considered a preferred form of my 25 invention, I desire the same to be understood as illustrative only and not as limiting said invention.

Having now described my invention, I claim:

- 30 1. In a metal window construction, a metal frame formed from sheet metal and having a portion of the pulley stile punched out to form hooks and a pulley assembly and casing mounted on the hooks and held in place 35 thereby.
- 2. A weight pocket device for windows, comprising a hollow casing having a side wall provided with an opening, a portion of the wall at an edge of the opening being 40 outwardly tapered and forming a shoulder for lateral entry of an edge of the cover, and means at the other edge of the opening and the cover for holding the cover in closed position.
- 45 3. A weight pocket device for windows, comprising a hollow casing having a side wall provided with an opening, a portion of the wall at an edge of the opening being outwardly tapered for forming a shoulder for the lateral entry of an edge of the cover, said edge of said cover having a flange and shoulder for respective engagement with the inner face and edge of said tapered portion for locating the cover in proper position and 50 55 means at the other edge of the opening and cover for holding the cover in closed position.
- 4. A sheet metal rail for window construction composing an integral sheet of metal 60 bent to provide a relatively long strip of substantially rectangular cross section, the metal of the rail being bent to provide along one side an outstanding flange of doubled thickness and a spaced inwardly extending 65 fold of double thickness providing a pocket,

and an intermediate seat, the metal forming the adjacent sides of the rail being bent at right angles to provide resilient flanges spaced apart to provide an open side opposite the reversely bent flanges, with the extremities of said flanges turned inwardly in open folds, and so that the walls of the folds extend substantially parallel.

In witness whereof, I hereunto subscribe my name to this specification.
